Patented May 18, 1915.

UNITED STATES PATENT OFFICE.

JACOB BREWER, OF HAZLETON, PENNSYLVANIA.

STOVE.

1,139,750.

Specification of Letters Patent. Patented May 18, 1915.

Application filed September 17, 1913. Serial No. 790,276.

To all whom it may concern:

Be it known that I, JACOB BREWER, a citizen of the United States, residing at Hazleton, in the county of Luzerne and 5 State of Pennsylvania, have invented a new and useful Stove, of which the following is a specification.

The device forming the subject matter of this application is adapted to be employed 10 as an adjunct to a heater of any sort, for the purpose of heating air, by means of the escaping products of combustion, the air, after having been heated, being returned to the combustion space of the heater or to the 15 ash pit of the heater, as may be deemed expedient.

It is within the scope of the invention to improve generally and to enhance the utility of, devices of that type to which the 20 present invention appertains.

With the above and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed without 30 departing from the spirit of the invention.

In the drawing:—Figure 1 shows the invention in vertical section, applied to a cook stove; Fig. 2 is a vertical section showing the invention applied to an up- 35 right heater of the furnace or parlor stove type; Fig. 3 is a vertical section showing a modified form of the invention adapted to be installed in stoves which are already in use.

40 The device herein disclosed is adapted to be employed in connection with a heater of any sort, and the term "heater" is to be construed to mean any structure from which products of combustion escape.

45 In the present instance, and by way of illustration, the heater in Fig. 1 has been shown in the form of a cook stove 1 including an oven 2 and grate 3, the combustion chamber being indicated at 4 and the 50 ash pit at 5, the outlet pipe for the combustion chamber being shown at 6 and the flue or stove pipe at 7.

55 In Fig. 2, the heater 8 has been shown as of the upright form, and may be a furnace or parlor stove so called. The fire pot is shown at 9 and the grate at 10, the outlet pipe for the products of combustion being

indicated at 11. The space 12 within the fire pot 9 constitutes a combustion chamber and the ash pit is shown at 14. The flue, 60 chimney or stove pipe is indicated at 15.

In Fig. 3, the heater is shown in the form of a cook stove 16 having an oven 17 and a grate 18, the combustion chamber being indicated at 19 and the ash pit at 20, the outlet pipe for the products of combustion being shown at 21 and the flue or stove pipe 65 being shown at 22.

In carrying out the invention there is provided a drum 23 provided at its upper end 70 with a collar 24 equipped with a damper 24^a. The collar 24 receives the flue 7 in Fig. 1, the flue 15 in Fig. 2, and the flue 22 in Fig. 3. In all figures of the drawing, a sinuous flue 26 is disposed within the drum 75 23, and it will be understood that the flue 26 may be placed in any desired manner within the drum. In all figures of the drawing, one end of the flue 26 is equipped with a funnel shaped air inlet 27, opening 80 through the wall of the drum 23. As shown in Figs. 1 and 3, the drum 23 terminates at its lower end in a collar 25 co-operating with the outlet pipe 6 in Fig. 1 and with the outlet pipe 21 in Fig. 3. 85

Referring particularly to Fig. 1, one end of the flue 26 is extended through the lower end of the drum 23 and is carried downwardly as indicated at 28, to the rear of the oven 2, the flue, thence, being carried 90 beneath the oven 2 as shown at 30, and being extended vertically in front of the oven 2 and beneath the grate 3 in the ash pit 5 as indicated at 29, the portion 29 of the flue being extended above the grate 3 and 95 into the combustion chamber 4 to form a branch 29^a. The portion 29 of the flue which lies below the grate 3 is equipped with an opening 31, located below the grate, and this opening 31 is controlled by a damper 32. The grate 3 acts as a stop for the damper 32 when the latter is swung to an open position. The damper 32, therefore, is always held above the opening 31 and ashes from the grate 3 cannot drop into 105 the flue or conduit through the opening 31. In the upper portion of the branch 29^a or in any other part thereof is disposed a damper 33.

Referring to Fig. 2, the lower portion of 110 the drum 23 is provided with an extended collar or pipe 34 co-operating with the upper or exposed end of the outlet pipe 11. The terminal convolution of the flue 26, in

Fig. 2, is extended outside of the drum 23 as shown at 35, the pipe 35 being bifurcated to form branches 36 and 37, the branch 36 entering the fire pot 9 and the branch 37 entering the ash pit 14. In the branch 37 is disposed a damper 38 and a damper 39 operates in the branch 36.

Fig. 3 illustrates the invention as constructed and applied to cook stoves or the like which are already in use. Under such circumstances, the terminal convolution of the flue 26 is carried horizontally as indicated at 40, the pipe being offset as indicated at 50, so that the portion 40 lies to one side of the stove and outside of the wall thereof. The portion 40 of the flue is bifurcated to form branches 41 and 42, the branch 42 communicating with the ash pit 20 and the branch 41 communicating with the combustion chamber 19. Disposed at any point in the branch 42 is a damper 43 and another damper 44 operates in the branch 41.

In practical operation, referring to Fig. 1, the fuel is consumed upon the grate 3, as usual, the products of combustion passing through the outlet 6, the collar 25, the drum 23, the collar 24 and the flue 7, the outward passage of the products of combustion being regulated by manipulating the damper 24. Air will enter the flue 26 through the inlet 27 and will be heated by the products of combustion as the same pass through the drum 23. The draft through heater 1 and through the drum 23 will cause the heated air within the flue 26 to be drawn downwardly through the portions 28, 30 and 29 of the flue. When it is desired to increase the draft, the damper 33 is closed and the damper 32 is open. Thereupon, the air traversing the flue 26—28—30—29 will be delivered below the grate 3. By closing the damper 32 and by opening the damper 33, the heated air will be delivered into the combustion space 4, above the grate 3.

By the operation above described, it will be seen that waste products of combustion passing out of the stove pipe will be made efficient to heat air which, after being heated will be delivered within the contour of the heater either above or below the grate 3, as may be desired.

Referring to Fig. 2, the operation of the structure remains substantially as above described. By closing the damper 39 and opening the damper 38, heated air will be delivered below the grate 10. By closing the damper 38 and opening the damper 39, the heated air will be delivered into the combustion chamber 12.

Referring to Fig. 3, by closing the damper 44 and opening the damper 43, the heated

air will be delivered below the grate 18 whereas by closing the damper 43 and opening the damper 44, the heated air will be delivered into the combustion space 19 above the grate 18.

The device herein disclosed although simple in construction and of few parts, will be found thoroughly efficient for the ends in view and will operate to abstract from the outgoing products of combustion, heat otherwise wasted, and to render the same efficient within the contour of the heater.

Having thus described the invention, what is claimed is:—

1. In a device of the class described, a heater having a grate defining an ash-pit and a combustion space, the heater having an outlet communicating with the combustion space; a drum resting on the heater and surrounding the outlet, the drum having an opening in its top; a flue supported on the drum and surrounding the opening therein; a pipe curved within the drum and having its ends extended through the wall of the drum at the bottom of the drum, one end of the pipe constituting an air inlet and being located close to the top of the heater and directly above the top of the heater whereby the hot air rising from the top of the heater may be drawn into the air inlet, the other end of the pipe having a pair of outlets, one of which outlets communicates with the combustion space of the heater, the other of which outlets communicate with the space below the grate; and a means for individually controlling the outlets.

2. In a device of the class described, a heater having a grate and provided with an outlet flue for the products of combustion; a casing interposed in the flue; a conduit passing through the casing, one end of the conduit being open to the atmosphere and the other end of the conduit passing into the heater below the grate and being upwardly extended above the grate, the conduit having an opening located below the grate; and a damper controlling the opening; the grate acting as a stop for the damper when the latter is moved to an open position, whereby to maintain the damper above the opening and to prevent ashes from falling from the grate into the conduit through the opening.

In testimony that I claim the foregoing as my own, I have hereto affixed my signature in the presence of two witnesses.

JACOB BREWER.
